UNITED STATES PATENT OFFICE.

GEORGE C. LYNCH, OF NEW YORK, N. Y.

LAMP.

1,264,669.

Specification of Letters Patent. Patented Apr. 30, 1918.

Application filed February 21, 1916. Serial No. 79,666.

To all whom it may concern:

Be it known that I, GEORGE C. LYNCH, a citizen of the United States, and a resident of the city of New York, borough of Manhattan, in the county and State of New York, have invented a new and Improved Lamp, of which the following is a full, clear, and exact description.

Among the principal objects which the present invention has in view are: to totally diffuse the light emitted by the illuminating element of a lamp; to conceal the illuminating element while reflecting the light thereof from the fixture supporting the same; to vary the diffusion of the light for obtaining a softened glow in the space above the lamp while concentrating part of the light adjacent the base of the lamp for reading purposes; and to provide means for variously coloring the light diffused.

Drawings.

Figure 1 is vertical section of a lamp constructed and arranged in accordance with the present invention, a fragment of the supporting pedestal being shown;

Fig. 2 is a side elevation of the same.

Description.

As seen in the drawings, the pedestal is surmounted by an opaque receptacle 8. The receptacle 8 is preferably designed and ornamented to conform with the pedestal 7. The perimeter of the receptacle is raised above the electric lamp globe 9, which usually forms the illuminating element in lamps of this character.

The receptacle 8 may be furnished with an auxiliary reflector 10. The reflector 10 has an opening through which the socket 11 of the lamp extends. The switch with which the lamp is provided is operated by a drop chain 12, which passes through the ornamentation at the top of the pedestal 7, advantage being taken of any suitable form or ornamentation for this purpose.

When so equipped it will be seen that the light emanating from the illuminating lamp is reflected upward from the cup or receptacle 8. The light thus emitted is variously diffused by a shade supported on elongated pins 13, the ends whereof are curled to form feet 14, which extend below hooks 15 supported in the perimeter of the receptacle 8, as shown best in Fig. 1 of the drawings. The pins 13 are all secured to a ring 16, covering

which is a color screen 17, and encircling which is a head 18 for a canopy 19. The canopy 19 is translucent, and is usually selected for its value as a color screen, said canopy being secured to a hoop 20.

To the hoop 20 is also bound a lining 21, the office of which is to reflect the light thrown upon its inner surface downward through the hoop 20 for illuminating the area below the shade. The lining 21 is translucent so that a modified light passes therethrough to the canopy 19, while the major portion of the light is reflected or concentrated in the area below the shade. A fringe 22 or other suitable ornamentation is provided. The fringe 22 is bound upon and supported by the hoop 20.

When in service the light emitted from the lamp is reflected by the reflector 10 upwardly from the receptacle 8. The light which passes through the screen 17 is broken up in the passage and creates a glow above the screen, and prevents a reflection from the ceiling above to produce what is known as indirect illumination. In other words, one of the purposes of the present invention is to avoid the indirect illumination resulting from uninterrupted transmission of light to the ceiling above a lamp.

The light which passes the perimeter of the receptacle 8 to the lining 21, is largely reflected thereby to the area below the shade. This lining may be selected with regard to the color of the reflected light, as well as the color of the diffused light, which is transmitted through the canopy 19. It will be understood that if a lining having a green tint is used, the reflected as well as transmitted light will take on a modified tint of the same value.

It will be observed that when lamps constructed and arranged in accordance with the present invention are illuminated, the illuminating element is concealed, but it will also be noted that the shade is softly illuminated while below the shade a relatively bright light is reflected suitable for reading purposes and above the shade an illuminated area is formed for general lighting purposes.

Claims.

1. A lamp comprising, in combination, a supporting standard, an illuminant thereon, an inverted cupped member about said illuminant adapted to reflect the light rays di-

vergingly upward, and a shade about said elements including inner reflecting and translucent material designed to redirect a portion of the reflected and direct rays downward, 5 and outward translucent material designed to modify the rays transmitted through said inner material.

2. A device of the character described, in combination, an illuminant, an inverted 10 opaque cupped member thereabout adapted to reflect the light rays divergently upward, and a shade about said elements including inner reflecting and translucent material designed to redirect the major portion of the

reflected and direct rays downward, and 15 outer translucent material designed to modify the rays transmitted through said inner material, said materials also having a definite color relation to effect harmonious modification of the reflected and transmitted 20 light.

In testimony whereof I have signed my name to this specification in the presence of two subscribing witnesses.

GEORGE C. LYNCH.
